THROTTLING DEVICE FOR INTERNAL COMBUSTION ENGINES

Otto Winter, Himmelkron, Germany

Application February 11, 1931, Serial No. 515,037,
and in Germany February 13, 1930

3 Claims. (Cl. 123—196)

My invention relates to throttling devices for internal combustion engines.

It is an object of my invention to provide an automatic control for an air throttle or choke valve. To this end I provide means for operating the throttle which means is controlled by the lubricating oil of the engine.

In a preferred embodiment of my invention I provide a cylinder with a barrel therein which is secured on the shaft of the air supply throttle 10 and equip the barrel with a vane or piston which is fitted to slide in the cylinder. Rotation is imparted to the barrel by connecting the chamber of the cylinder in which the piston slides with the lubricating system of the engine.

The vane or piston is so pitched with respect to the air throttle that the throttle is in its closing position when the piston is in its initial position. When the engine is started oil from the 20 pressure lubricating system begins to flow in the cylinder and the barrel is rotated, opening the air throttle until the piston strikes a check in the cylinder. In this final position of the piston the throttle is full open.

25 When the engine is started the oil is cold and comparatively thick. The consequence is that the air throttle or choke valve is opened more or less gradually in conformity with the viscosity of the oil and rich mixture is supplied to the engine for a period which is a function of the viscosity. The rich mixture is favorable for starting. Later on when the oil becomes warm and its viscosity decreases the throttle is operated in the usual manner and the engine is supplied with 30 normal mixture.

When the engine is shut down the air throttle is closed automatically by the one-sided gravity action of the piston on the barrel, or by a spring or the like.

40 If the lubricating system of the engine fails the air throttle is not operated and the engine cannot start because its sparking plugs are flooded by the excess of fuel supplied with the rich mixture. If the system fails while the engine 45 runs the same will occur so that under all conditions operation of the engine without lubrication is prevented.

If the oil becomes too thin the engine is not 50 lubricated properly, as the pressure of the thin oil is not able to operate the air throttle properly, and it may even fail to operate the throttle at all. The engine runs irregularly which will be noticed by the driver, or it stops altogether.

In the drawing affixed to this specification and 55 forming part thereof a throttling device embody-

ing my invention is illustrated diagrammatically by way of example.

In the drawing

Fig. 1 is an elevation of the device with the cover of the cylinder removed.

Fig. 2 is a plan view, and

Fig. 3 is a section on the line III—III in Fig. 1.

Referring now to the drawing, 1 is the air suction pipe of the engine, 2 is the air throttle or choke valve in the suction pipe, 3 is the throttle shaft, and 4, 5 are its bearings in the pipe 1. 6 is the cylinder which may be integral with, or secured to, the suction pipe 1, 7 is a barrel on the shaft 3 which makes a tight fit in a circular recess 8 of the cylinder 6, and 12 is a vane or piston on the barrel which is mounted to slide in a chamber 11 of the cylinder 6 as the barrel oscillates. 9 and 10 are pipes at the lower and upper ends of the chamber 11, respectively. The pipe 9 is connected to the pressure oil supply 75 line and the pipe 10 is connected to an oil filter or a return line to the sump by suitable pipes, not shown. 13 and 16 are checks for limiting the stroke of the vane or piston 12 in the chamber 11, the barrel 7 being recessed at 17 for the reception of the check 16. 15 is the cover of the cylinder 16. 14 is a deflector extending from the upper end of the lower pipe 9 toward the edge of the barrel 7.

Fig. 1 shows the parts in their initial or starting position. The throttle 2 is vertical, the piston 12 is at the lower end of its stroke. When the engine is started oil is admitted to the lower face of the piston 12 by the pressure lubricating system and gradually moves the piston upwards until it strikes the upper check 13. In the upper final position of the piston the air throttle 2 is full open. When the flow of the oil ceases the piston is returned to its initial position in which it is arrested by the check 16, as shown in Fig. 1. The piston 12 returns to its initial position by gravity or means, not shown, such as a spring, may be provided for returning it.

I wish it to be understood that I do not desire 100 to be limited to the exact details of construction shown and described for obvious modifications will occur to a person skilled in the art.

In the claims affixed to this specification no 105 selection of any particular modification of the invention is intended to the exclusion of other modifications thereof and the right to subsequently make claim to any modification not covered by these claims is expressly reserved.

I claim:

1. An automatic fuel mixture control device 110

for internal combustion engines comprising an air throttle, and means controlled by the lubricating oil of the engine for operating said air throttle.

- 5 2. An air throttling device for internal combustion engines with a pressure lubricating system, comprising a suction pipe, a throttle shaft mounted to rotate in said suction pipe, an air throttle on said shaft, a cylinder on said suction pipe, a barrel in said cylinder secured on said shaft, an oscillating piston in said barrel mounted for partial rotation in a chamber of said cylinder, and means connected to opposite sides of said chamber for admitting oil from the pressure lubricating system of the engine to opposite sides of said piston.
- 10 15

3. An air throttling device for internal combustion engines with a pressure lubricating system, comprising a suction pipe, a throttle shaft mounted to rotate in said suction pipe, an air throttle on said shaft, a cylinder on said suction pipe, a barrel in said cylinder secured on said shaft, an oscillating piston in said barrel mounted for partial rotation in a chamber of said cylinder, checks for limiting the stroke of said piston, and means connected to opposite sides of said chamber for admitting oil from the pressure lubricating system of the engine to opposite sides of said piston.
